UNITED STATES PATENT OFFICE.

THOMAS C. CADWGAN, OF SPRINGFIELD, OHIO.

GRINDING-MILL.

1,144,689.

Specification of Letters Patent. Patented June 29, 1915.

Application filed November 5, 1914. Serial No. 870,386.

To all whom it may concern:

Be it known that I, THOMAS C. CADWGAN, a citizen of the United States, residing at Springfield, in the county of Clark and 5 State of Ohio, have invented certain new and useful Improvements in Grinding-Mills, of which the following is a specification.

My invention relates to improvements in 10 grinding mills and particularly to grinding mills of the duplex type.

An object of the invention is to provide a mill with a central feed; that is, a mill so constructed that the respective pairs of 15 grinding plates will be located on opposite sides of the passage from the hopper.

A further object of the invention is to provide simple and effective means for adjusting the grinding plates for coarse or fine 20 grinding.

A further object of the invention is to provide a mill of the character referred to which will be simple in construction, economical in manufacture and effective in use.

25 In the accompanying drawings: Figure 1 is a longitudinal section of the grinding mills embodying my improvement, the section being taken on the line 1—1 of Fig. 3. Fig. 2 is a top plan view of the same with the hopper and breakers removed. Fig. 3 is an end view of the mill. Fig. 4 is a detail of a portion of the plate adjusting mechanism.

Like parts are indicated by similar characters of reference in the several views.

In the said drawings 1 represents a stationary portion of the main casing and 2 a movable portion of the same. The stationary portion 1 is supported upon a suitable 40 supporting frame 3 and the movable portion is slidably mounted upon rods 4 and 5 which are connected with and project longitudinally from the stationary portion 1 of the casing; said rods 4 and 5 being secured 45 in the bosses 6 on the sides of the stationary part 1 and the movable part 2 having bosses 7 which are slidably mounted upon said rods. The respective casing parts where they meet are shouldered and overlap as 50 shown in Fig. 1.

The stationary portion 1 of the casing

carries a stationary grinding bur 8 and the movable portion 2 of the casing also has a stationary grinding bur or plate 9; the respective grinding plates 8 and 9 having 55 shouldered overlapping portions as shown in Fig. 1. Journaled in suitable bearings formed upon the respective casing portions is a driven shaft 10, which shaft has rotatably connected therewith grinding plates 60 11 and 12 which coöperate with the respective stationary plates 8 and 9; said plates 11 and 12 being splined to the shaft so as to be capable of being removed therefrom when desired but held against longitudinal 65 movement thereon by pins 11^a and 12^a. Also splined to said shaft 10 between the plates 11 and 12 are crushers and conveyers 13 and 14, the spiral ribs 15 of which are arranged in opposite directions so that the 70 conveyor 13 will convey the material to the grinding plates 9 and 12 and the conveyor 14 will convey the material to the grinding plates 8 and 11.

Suitable discharge openings (not shown) 75 are provided at each end of the casing for the discharge of the ground material.

The shaft 10 is longitudinally movable in its bearing within certain limits determined by the distance separating the stationary 80 and revoluble grinding plates.

In order to provide for adjusting the grinding plates, for the purpose of regulating the fineness of the ground material, I have provided means for moving the movable 85 casing portion 2, together with the grinding plate 8, longitudinally upon the guides 4 and 5 so as to permit of a movement of the shaft 10 and its revoluble plate.

Pivots connected to the bearing 16 of 90 the movable portion of the casing is a lever 17, said lever being provided with an elongated opening 18 to which said bearing 16 extends and being pivotally connected to said bearing by the pivot screw 19. One 95 end of the lever is bifurcated at 20 and straddles the grooved hub portion 21 of the hand wheel 22, which hand wheel is mounted upon the screw-threaded guide rod 4. The opposite end of the lever is provided 100 with an elongated opening 23 through which extends the guide rod 5 and this end of the

lever is pivotally connected to said rod 5 by a cotter pin 24.

As a result of this construction, by turning the hand wheel 22 the movable portion 2 of the casing can be moved in or out with respect to the stationary portion 1 so as to increase or diminish the space between the plates 8 and 9. For instance assuming the 5 grinding plates to be in their closest grinding relation, as shown in Fig. 1, if now, it is desired to adjust the plates farther apart, the hand wheel will be manipulated so as to throw the movable part of the casing 2 inwardly thus causing the plates 8 and 9 to 10 be brought closer together. The action of the ground material will then cause the two plates 11 and 12 to self-adjust themselves with respect to the plates 9 and 8 by the 15 movement of the shaft 10 longitudinally in its bearings.

The grinding casing is surmounted by the usual hopper 25 having the usual breakers 26 driven in any suitable way from the shaft 27, this construction being well known.

Having thus described my invention, I 25 claim:

1. In a grinding mill, a main casing, two 30 separate pairs of grinding members arranged in the same horizontal plane in said casing, each pair consisting of a revolute and a non-revolute member, a drive shaft connecting said revolute members, the non-revolute members being located between the revolute members, means for adjusting the 35 non-revolute member of one pair relatively to the opposing revolute member, said shaft being capable of a limited longitudinal movement to permit said revolute members to self-adjust themselves relatively to the 40 non-revolute members, and a hopper connected with the upper portion of said casing and arranged to discharge the material therein between the non-revolute members, together with a conveyer connected with 45 said shaft for conveying said material in opposite directions to said grinding members.

2. In a grinding mill, a casing formed in 50 two sections, two pairs of grinding members therein, each pair consisting of a revolute and a non-revolute member, the non-revolute members being supported respectively by the casing sections and having a sliding engagement with each other, a driven shaft extending through said casing to which the 55 revolute grinding members are connected, and means for adjusting the casing sections relatively to each other to vary the distance between the non-revolute grinding members, said shaft being capable of a limited 60 movement through said casing to permit the revolute members to self-adjust themselves relatively to the non-revolute members.

3. In a grinding mill, a casing formed in

two sections, two pairs of grinding members 65 therein, each pair consisting of a revolute and non-revolute member, the non-revolute members being supported by the respective casing parts, a driven shaft extending through said casing to which the revolute grinding members are connected, and 70 means for adjusting one casing section to vary the distance between the non-revolute grinding members, said shaft being capable of a limited movement in either direction through said casing to permit the revolute 75 members to self-adjust themselves relatively to the non-revolute members at each adjustment of said casing section.

4. In a grinding mill, a casing formed in 80 two sections, one of which is movable relatively to the other, two pairs of grinding members located in said casing in the same horizontal plane, each pair consisting of a revolute and non-revolute member, said non-revolute members being carried by 85 the respective casing sections and being located between the revolute members, a driven shaft extending through said casing to which the revolute members are connected, and means for adjusting the movable casing section to vary the distance between the non-revolute members, said shaft being capable of a limited longitudinal 90 movement so as to permit the revolute grinding members to self-adjust themselves relatively to the non-revolute members at 95 each adjustment of said movable section.

5. In a grinding mill, a casing formed in 100 two sections, one section being slidably connected with the other, grinding members located in said casing, driven shaft extending through said casing, part of said grinding members being connected with said casing and part with said shaft, devices for 105 adjusting said slidable casing section for the purpose of varying the relation between said grinding members, said adjusting devices consisting in part of a pivoted lever pivotally connected with said slidable casing section, and an adjustable hand wheel 110 operatively connected to the free end of said lever.

6. In a grinding mill, a casing formed in 115 two sections, a stationary section and a movable section, a pair of supporting rods supported from said stationary section upon which said movable section is slidably mounted, grinding members located in said casing, a driven shaft extending through said casing, part of said grinding members 120 being supported by said casing and part connected with said shaft, devices for adjusting said movable casing section for the purpose of varying the relation between said grinding members, said adjusting devices consisting of a lever pivotally 125

nected to the one of said supporting rods and also pivotally connected to said movable section, and a hand wheel adjustably mounted on a screw threaded part of the other 5 supporting rod, having a grooved hub, the free end of said lever having a bifurcated portion fitted over said hub.

In testimony whereof, I have hereunto set my hand this 17th day of October 1914.

THOMAS C. CADWGAN.
